UNITED STATES PATENT OFFICE

138,572

DESIGN FOR A TIRE SERVICING TOOL

Joseph B. Jarrell, Prosser, Wash.

Application May 1, 1944, Serial No. 113,420

Term of patent 14 years

(Cl. D54—13)

To all whom it may concern:

Be it known that I, Joseph B. Jarrell, a citizen of the United States, residing at Prosser, in the county of Benton and State of Washington have invented a new, original, and ornamental Design for a Tire Servicing Tool, of which the following is a specification, reference being had to the accompanying drawing, forming part thereof.

Fig. 1 is a front elevational view of a tire servicing tool embodying my new design; and

Figs. 2 and 3, respectively, are side and rear elevational views of the same.

I claim:

The ornamental design for a tire servicing tool, as shown.

JOSEPH B. JARRELL.
